CONTROL DEVICE WITH TWO PUSH BUTTONS
FOR TWO COLOURS BALL POINT PENSFrancis Levoine, Breganzona, Lugano, Switzerland,
assignor to Real Patentauswertungs Anstalt, Vaduz, Liechtenstein

Filed Apr. 22, 1963, Ser. No. 274,528

Claims priority, application Switzerland, Mar. 6, 1963,
2,878/63

8 Claims. (Cl. 120—42.13)

This invention relates to ball point pens, and more particularly to a pen casing adapted to hold a plurality of ball point cartridges, and to a control mechanism on the casing for selectively moving each cartridge between a writing position and a retracted position.

In its more specific aspects, the invention is concerned with a push button control device on a ball point pen casing adapted to move one of a plurality of cartridges into the writing position and thereby automatically to retract another cartridge which may have been in the writing position before.

An object of the invention is the provision of such a control device which is simple in its design and operation.

Another object is the provision of a control device composed of parts which are of very simple shapes so that they may be readily produced from plastics or metals by press operations.

Other objects and many of the attendant advantages will be readily appreciated as the same becomes better understood by reference to the following detailed description of a preferred embodiment, when considered in connection with the accompanying drawings in which:

FIG. 1 shows a ball point pen equipped with the casing of the invention in front elevational axial section;

FIG. 2 shows an actuating button of the pen of FIG. 1 in side elevation;

FIG. 3 shows a divider assembly of the pen in a view corresponding to that of FIG. 2;

Figs. 4 to 6 illustrate the cooperation of an actuating button of FIG. 1 with the divider assembly of FIG. 3 when the button moves from the inoperative position shown in FIG. 4 through an intermediate position illustrated in FIG. 6 into the operative position seen in FIG. 5.

Referring now to the drawing in detail, and initially to FIG. 1, there are shown two conventional ball pen cartridges *h*, *h'* which have flexible tubular ink reservoirs and a ball point mounted on an end of the reservoir. The cartridges are arranged in a pen casing with which this invention is more particularly concerned.

The casing has a generally cylindrical main barrel portion *b*. The ball point of the cartridge *h'* projects axially from an opening in a tapering end portion of the barrel. The other end of the main portion *b* is threadedly connected to a coaxial cap portion *i*. A partition *a* is fixed in the open end of the cap *i* in a diametrical plane.

A divider assembly best seen in FIG. 3 is axially secured between the partition *a* and a radial end face of the barrel portion *b* in the casing cavity. The divider assembly consists of three rod portions *k*, *k*₁, *k*₂ and a circular disc portion *k*₃. The four integral divider assembly portions constitute the four sides of an elongated frame. Locking projections *f*, *f*₁ project away from each other from the two opposite longer rod portions *k*₁, *k*₂ which are of resilient material. The two projections extend in a common plane perpendicular to the axis of the pen barrel and are somewhat nearer the short rod portion *k* than the disc portion *k*₃. A face of each projection *f*, *f*₁ nearer the short rod portion *k* slopes at an angle of approximately 45° toward the radial plane disc portion *k*₃. The face of each projection nearer the disc

2

portion slopes much less steeply toward the radial plane of the latter. In the installed condition of the divider, the rod portions *k*, *k*₁, *k*₂ and the projections *f*, *f*₁ extend in the plane of the partition *a*, as is evident from FIG. 1. The short rod portion *k* abuts against the partition, and the disc portion *k*₃ abuts against the aforementioned radial end face of the barrel portion *b*.

The divider separates two axially coextensive portions of the casing cavity in the cap portion *i*. Two actuating buttons *c*, *c'* are axially slidable in the respective cavity portions between an inoperative position in which the button *c* is shown to project outward from the casing cavity, and an operative position illustrated by the button *c'*.

15 As shown in FIG. 2, two axially elongated ribs *t*₁, *t*₂ project from the face of the button *c* opposite the button *c'*, and the latter is provided with corresponding ribs *t*_{1'}, *t*_{2'}. The dimensions of the ribs are such that they may move in simultaneous engagement with the divider without interfering with each other. The outer end faces *r*₁, *r*₂ of the ribs *t*₁, *t*₂ slope obliquely with respect to the barrel axis for conforming engagement with the less steeply sloping faces of the locking projections *f*, *f*₁. Near their inner ends, the sides of the ribs

20 *t*₁, *t*₂ which face each other have V-shaped notches *s*₁, *s*₂ which conforms to the locking projections *f*, *f*₁. The spacing *d* between the facing sides of the ribs *t*₁, *t*₂ is smaller than the spacing *d*₁ of the outer points of the locking projections *f*, *f*₁ in the relaxed condition of the 25 longer rod portions *k*₁, *k*₂ illustrated in FIG. 3. The ribs *t*_{1'}, *t*_{2'} of the button *c* have engagement faces *r*_{1'}, *r*_{2'} and V-shaped notches identical with the corresponding features of the button *c*, as is evident from FIG. 5.

30 The cartridges *h*, *h'* are held in respective recesses of the buttons *c*, *c'*, and the buttons are urged toward their inoperative positions by helical compression springs *e*, *e'* which abut against the disc portion *k*₃ of the divider assembly and against radial faces of the buttons. The cartridges *h*, *h'* are guided in their movement between the 35 writing position illustrated by the cartridge *h'* and the retracted position illustrated by the cartridge *h* in conforming openings of the disc portion *k*₃.

The operation of the afore-described apparatus will be described with references to FIGS. 4 to 6. In the position of the pen illustrated in FIG. 1, the actuating button *c* of the retracted cartridge *h* is in its inoperative position.

40 As shown in FIG. 4, the outer part of the divider assembly including the short rod portion *k* and parts of the longer rod portions *k*₁, *k*₂ are received between the ribs *t*₁, *t*₂. The projections *f*, *f*₁ are received in the conforming notches *s*₁, *s*₂, and the longer rod portions are in their relaxed or almost relaxed condition. Engagement of the less steeply sloping faces of the projections *f*, *f*₁ with the corresponding walls of the notches *s*₁, *s*₂ prevents outward movement of the button *c* under the urging of the spring *e*.

45 The actuating button *c'* of the cartridge *h'* which is in its writing position is simultaneously in the operative position shown in FIG. 5. The ribs *t*_{1'}, *t*_{2'} are in loose abutting engagement with the parts of the rod portions *k*₁, *k*₂ between the locking projections *f*, *f*₁ and the disc portion *k*₃. The end faces *r*_{1'}, *r*_{2'} of the ribs abuttingly engage the less steeply sloping faces of the locking projections *f*, *f*₁ under the urging of the spring *e'*, and thereby lock the button *c'* in the illustrated operative position.

50 When the button *c*, which is accessible from the outside of the casing, is moved axially in the direction of the arrow *p*, the two long rod portions *k*₁, *k*₂ of the divider are pushed radially toward each other by the camming engagement with the steeply sloping, lock-releasing walls of the notches *s*₁, *s*₂ of the ribs *t*₁, *t*₂ as shown in

FIG. 6 to permit axial passage of the projections f, f_1 , between the ribs t_1, t_2 under external pressure against the restraint of the spring e . The movement of the projections f, f_1 away from their locking position simultaneously permits the ribs t_1', t_2' to escape outward from the position illustrated in FIG. 5 under the force of the spring e' . When the button c is fully depressed into the inoperative position, the locking projections f, f_1 resiliently return to their locking position. If pressure on the button c is relaxed in the position of the button shown in FIG. 6, both buttons are moved by their springs into their inoperative positions, and both ball points are retracted.

Obviously, many modifications and variations of the present invention are possible in the light of the above teachings. It is therefore to be understood that within the scope of the appended claims, the invention may be practiced otherwise than as specifically disclosed.

I claim:

1. A casing for a ball point pen comprising, in combination:

- (a) a barrel having an axis and formed with an axially elongated cavity;
- (b) a divider member secured in said cavity against axial movement, said divider member extending in an axial plane and dividing an axial section of said cavity into two portions, said divider member including two axially elongated members of resilient material, respective portions of said elongated members being resiliently movable toward and away from each other in said plane transversely of said axis;
- (c) locking means secured on said divider member and projecting therefrom in said plane in a direction transverse of said axis, said locking means being resiliently movable in said plane toward and away from a locking position, said locking means including two locking members respectively secured on said portions of said elongated members for movement toward and away from each other, said locking members being remote from each other when said locking means are in said locking position;
- (d) two actuator members axially slidable in respective ones of said portions between respective operative and inoperative positions;
- (e) engagement means fixedly fastened on each actuator member for axially abutting engagement with said locking means when said locking means is in said locking position thereof;
- (f) lock releasing means fixedly fastened on each actuator member and engageable with said locking means for moving the same in said transverse direction away from said locking position thereof when said actuator member moves from said inoperative toward said operative position thereof; and
- (g) resilient means permanently urging each actuator member to move from said operative toward said inoperative position thereof, said engagement means axially abutting against said locking means under the urging of said resilient means when said actuator member is in the operative position thereof and said locking means is in said locking position.

2. A casing as set forth in claim 1, further comprising abutment means on said divider member, said abutment means axially abutting against said engagement means under the urging of said resilient means when said actuator member is in said inoperative position thereof.

3. In a ball pen, in combination:

- (a) a barrel having an axis and formed with an axially elongated cavity;
- (b) a divider assembly secured in said cavity against axial movement, said assembly including
  - (1) a plurality of rod members extending in a common axial plane, said plane dividing an axial section of said cavity into two portions;
  - (2) two of said rod members being elongated in a

an axial direction and being spaced from each other in a direction transverse of said axis,

- (3) a disc member axially secured in said barrel cavity and integrally fastened to respective axial end portions of said two rod members, and
- (4) a locking member projecting in said plane from at least one of said two rod members in said transverse direction away from the other one of said two rod members, said one rod member being of resilient material;
- (c) two actuator buttons axially slidable in respective ones of said cavity portions between respective operative and inoperative positions;
- (d) an integral rib projecting from each actuator button toward the other actuator button, each rib having

(1) a cam face obliquely inclined relative to said directions and engageable with said locking member for resiliently displacing said locking member toward the other of said two rod members in said transverse direction when said button moves from said inoperative toward said operative position, and

(2) an abutment face engageable with said locking member for preventing movement of said button from said operative toward said inoperative position; and

(e) yieldably resilient means permanently urging each button to move from said operative toward said inoperative position.

4. In a pen as set forth in claim 3, a third one of said rod members extending in said transverse direction and integrally connecting respective terminal portions of said two rod members axially spaced from said disc member.

5. In a pen as set forth in claim 4, said third rod member being arcuately curved.

6. In a pen as set forth in claim 5, said disc member being formed with two openings spaced in said transverse direction; and a cartridge member secured to each of said buttons and slidably received in a respective opening of said disc member for axial movement with the respective button.

7. In a ball pen, in combination:

- (a) a barrel having an axis and formed with an axially elongated cavity;
- (b) a divider assembly secured in said cavity against axial movement, said assembly including

- (1) a plurality of rod members extending in a common axial plane, said plane dividing an axial section of said cavity into two portions,
- (2) two of said rod members being elongated in an axial direction and being spaced from each other in a direction transverse of said axis,
- (3) a disc member axially secured in said barrel cavity and integrally fastened to respective axial end portions of said two rod members, and
- (4) a locking member projecting in said plane from each of said two rod members in said transverse direction away from the other one of said two rod members, said rod members being of resilient material;

(c) two actuator buttons axially slidable in respective ones of said cavity portions between respective operative and inoperative positions;

(d) two axially elongated integral ribs projecting from each actuator button toward corresponding ribs on the other actuator button, said ribs being spaced from each other in said transverse direction on each button, and said two rod members being received between said ribs, each rib having

(1) a face obliquely inclined relative to said directions and engageable with a coordinated one of said locking members for resiliently displacing the same toward the other locking member in said transverse direction when said button

- moves from said inoperative toward said operative position thereof, and
- (2) an abutment face engageable with the co-ordinated locking member for preventing movement of said button from said operative toward said inoperative position; and
- (e) yieldably resilient means permanently urging each button to move from said operative toward said inoperative position.
8. In a pen as set forth in claim 7, said disc member being formed with two openings spaced in said transverse direction; and a cartridge member secured to each of said buttons and slidably received in a respective opening of said disc member for axial movement with the respective button.
